UNITED STATES PATENT OFFICE.

VIRGIL P. WARREN, OF ATLANTA, GEORGIA.

REFRIGERATOR ICE TANK.

Application filed November 28, 1924. Serial No. 752,706.

This invention relates to improvements in refrigerator ice tanks and more particularly to a specific construction and arrangement of air conducting flues which extend angularly through the said tank.

An object of the invention is to provide an improved refrigerator ice tank in which there are a plurality of inwardly slanting air conducting flues through which hot air 10 in the refrigerator may pass, and while traveling through the said flues will be refrigerated and discharged on a line with the shelves in the refrigerator.

A further object of the invention is to provide a refrigerator ice tank not only with a plurality of angled air conducting flues but also with a centrally disposed vertically extending flue which increases in diameter from the top to the bottom of the said tank 20 whereby the hot air at the extreme top of the refrigerator case over the top of the tank will be permitted to pass down through the central flue and be refrigerated.

Other objects will appear as the description proceeds.

In the accompanying drawings which form a part of my application,

Fig. 1 is a perspective view of my improved refrigerator ice tank; and

Fig. 2 is a sectional view taken through one end of the refrigerator and through the ice tank, showing more particularly the arrangement and positioning of the several flues in the tank.

Like characters of reference are used throughout the following specification and the accompanying drawings to designate corresponding parts.

My improved refrigerator ice tank is adapted to be used in any type of refrigerator, but for purposes of illustration I have shown the same positioned in an elongated type of refrigerator 1 having the spaced shelves 2, and usual drain 3.

The refrigerator ice tank 4 is substantially rectangular in shape, but is preferably slightly tapered at its front and back from the top to the bottom thereof. One or more wheels 5 are mounted at the opposite sides 50 of the refrigerator tank in any desired manner and are adapted to be supported on and to operate upon the track members 6 which are supported by suitable brackets 7 attached to the inner walls of the refrigerator case 1.

The ice tank 4 is further provided with a

plurality of spaced angled air conducting flues 8 which are of equal diameter throughout their lengths and extend on a downward slant from the adjacent end of the refrigerator case to the interior thereof. These flues 8 are positioned in pairs, one above the other, as best illustrated in Fig. 1 of the drawings and are somewhat nearer the adjacent walls of the front and back of the tank than they are to the center thereof.

An especially important feature of construction which I have provided consists of a central air conducting flue 9 which extends vertically from the top to the bottom of the ice tank and is positioned centrally of the pairs of flues 8. The central flue 9 is provided with a fairly small opening at its upper end and increases in size throughout its length. The upper end of the flue 9 is positioned nearer to the adjacent end wall of the refrigerator case 1 than is the lower end thereof and serves to conduct the hot air from the space over the ice tank 4 down through the said flue where it is refrigerated, 80 and to discharge the same air into the bottom of the case 1 in a direction toward the center thereof and underneath the lower shelf 2. A suitable brace 10 may be used to hold the upper end of the flue 9 in fixed position. A handle 11 may be attached to the front of the ice tank 4 so that the said tank may be withdrawn from the interior of the case 1 upon the tracks 6.

The tank 4 is adapted to be filled with crushed ice and salt and will be provided with a suitable drain so that the drain water may pass therethrough and out through the drain passage 3 in the lower part of the case 1 directly under the said tank 4.

In my improved construction I find that the warmer air in the refrigerator case will naturally seek the highest level and will pass down through the air conducting flues 8 where the same will be refrigerated and discharged along the shelves 2, while the warmer air immediately over the ice tank will pass down through the vertical flue 9 and be refrigerated and discharged under the lower shelf 2. In this manner there will be a continuous circulation of the air in the refrigerator and the warm air will pass continuously through the several flues to be refrigerated and will thereby keep the temperature in the refrigerator case in a refrigerated condition.

Many minor changes in detail of construc-

tion may be resorted to without departure from the spirit of the invention.

I claim:

In combination with a receptacle, a track secured to and spaced from the end wall of said receptacle, a second track, means for supporting said second track from the top of said receptacle, a tank slidably mounted on said tracks and having its top spaced from the top of said receptacle, said tank comprising a container for refrigerant material having a plurality of air conducting tubes extending transversely thereof, an air

conducting flue extending from the bottom of said container to and flush with the top 15 thereof, a brace extending from the sides of said container to the top of said flue, said tubes being inclined to the horizontal downwardly from the end of said container adjacent the end of said receptacle, and shelves 20 horizontally supported in said receptacle with their ends immediately below the adjacent ends of said tubes.

In testimony whereof I affix my signature.

VIRGIL P. WARREN.
